[57] ABSTRACT

A fluid translating device for a pressure fluid system comprising expandable chamber units, and working members therein, so combined and working in unison as to divide fluid from a source for delivery in equal parts to other sources. When the units are of even number the device is bidirectional in that it will divide flow when flow is in one direction in the fluid system or will combine flow when flow in the same system is in the opposite direction. Each unit (e.g., cylinder and piston) has three ports for communicating with a source and two additional ports respectively connected to a port communicating with the expandable chamber of another unit, whereby fluid from a source drives one working member (piston) which itself translates fluid to another source. In a preferred embodiment, two units valve each other, and effective ports are switched as a piston moves through a 90° position.

FLUID TRANSLATING DEVICE HAVING EXPANSIBLE CHAMBERS

This invention relates to self-valving devices which may be used for a variety of applications. These include, but are not limited to, such devices as flow dividers/combiners, transfer units, intensifiers, hydraulic circuit breakers, and flow meters. Aircraft serve a good example of where such devices may be employed; however, in addition to aircraft, other types of vehicles and/or stationary hydraulic systems may use these devices for similar purposes.

Aircraft embody controls which require equal and concurrent movement; thrust reverser flaps on jet engines, so-called leading edge devices on wings, lift flaps, and spoilers are examples. Additionally, transfer units may be employed for interconnecting hydraulic power from one system to another without interchange of system's fluids. Intensifiers may be used to increase operating pressures in order to obtain smaller sized actuators where space and aerodynamic considerations are a factor. Hydraulic circuit breakers may be used to protect portions of a hydraulic system. Deintensifiers may be used where high pressure low flow is converted to low pressure high flow; a fuel transfer unit driven by an aircraft hydraulic system is an example. The use of flow meters is obvious, both for aircraft and other purposes. The present invention may be applied to all of these.

Fluid divider/combiner or fluid proportioning devices are known such as U.S. Pat. No. 2,593,185 where a main stream of entrant fluid is proportioned within internal chambers and delivered to a pair of outlets, utilizing proportional valve means. There, however, pressure responsiveness is a very limiting factor, and one object of the present invention is to develop a flow divider/combiner able to divide a main stream of fluid equally between two branches or outlets without in any way depending upon a pressure factor. Additionally, flow in the reverse sense, or when the unit is acting as a combiner, will combine proportionally from each of the inlets. One feature of the present invention is that when acting as a divider, if an obstruction is encountered giving rise to an imbalance of pressure in one of the two outlet systems, the device will still deliver equal amounts of fluid to each of the outlet systems. Should the obstruction cause the pressure in one of the outlet systems to reach that of the supply pressure, the unit will stall thus positioning each of the actuators in the outlet system in identical positions. An additional feature of the device is that when in the combining mode, should something restrict the supply to the divider/combiner from one of the sub-systems, the unit will operate at a speed which is governed by that of the lowest pressure of the two supply sub-systems. Should jamming of an actuator occur, supply to the divider/combiner would be stopped to one side of the divider/combiner. The unit would stall, thus again positioning both actuators in identical positions.

It is obvious that such things as fan thrust reverser flaps, lift flaps, leading edge devices, or speed brakes, and similarly configured control devices operating out of parallel (not synchronized) can cause an aircraft to go into an unbalanced control mode. It is imperative that such control systems be operated to prevent an imbalance from occurring, otherwise loss of control of aircraft could occur.

In the chemical industry there are many instances where a source of fluid is to be divided and delivered in equal proportions to mixing chambers of reactor vessels, or it may be desirable to mix fluids in proportions.

5 The present invention is useful in this regard as well.

It can be seen from the foregoing that a need exists for a flow divider/combiner. Other applications are obvious for transfer units, intensifiers/de-intensifiers, and hydraulic circuit breakers. It may be stated categorically 10 that the present invention represents a magnitude of applications in various configurations.

Objects of the present invention will be apparent from the following description and claims and are illustrated in the accompanying drawings which, by way of 15 illustration, show preferred embodiments of the present invention and the principles thereof. Other embodiments of the invention employing the same or equivalent principles may be used and structural changes may be made as desired by those schooled in the art without 20 departing from the present invention.

FIG. 15 is a diagrammatic view showing one form of 75 commercial utility of the apparatus shown in FIG. 12;

FIG. 16 is a schematic view of a three cylinder 80 arrangement;

FIG. 17 is a diagrammatic view showing utility of two 85 mutually exclusive three cylinder arrangements; and

FIGS. 18 and 19 show embodiments where a three- 90 landed piston may be used.

GENERAL STATEMENT; GENERAL RULES

The devices of the present invention comprise an even number of expandable chamber units having working members therein moving repetitiously between a first and second position. During movement the working member in each unit alternately expands and contracts two expandable chambers, such that as one chamber

ber is being expanded the other or opposite one is being contracted.

In the specific embodiments, the expandable chamber units are cylinders and each working member is a reciprocal piston. When at one limit position of an operating cycle defined as 360°, which may be taken as the 0° or 360° position, the piston completely contracts a first expandable chamber and completely expands a second expandable chamber; and as the piston moves through a 90° position to a 180° position, the first chamber undergoes expansion as the second chamber is being contracted, the first chamber being completely expanded and the second chamber being completely contracted as the working member attains the 180° position. When the piston reverses, moving from the 180° position through a 270° position back to zero, expansion and contraction are reversed.

TWO CYLINDER ARRANGEMENT AND ADDITIONAL GENERAL RULES (FREE RUNNING PAIR)

As an introduction to the cyclically operable expansion chamber devices of the present invention, consideration shall first be given to the construction of a cylinder and related piston used for translating fluid between a main source and two branches. FIG. 1 is a schematic illustration of a cylinder 15 incorporating a piston or spool 16, the piston being located in a first position at one extremity of the cylinder; FIG. 1A shows the same piston in its intermediate position, the center or 90° position; FIG. 1B shows the same piston in the other extremity or 180° position.

The cylinder has two expandable end chambers 21 and 22 having ports P affording ingress and egress of fluid under pressure. Thus the piston will be moved as by the admission of pressurized fluid to the left-hand port P, FIG. 1, shifting the piston to its right-hand limit position shown in FIG. 1B.

The heads of the piston are afforded by lands 16A and 16BB at the remote ends of the piston. Additionally, the piston includes two intermediate lands 16C and 16D with grooves or reduced areas therebetween, the arrangement being such as to define three interior passages or chambers 20, 23 and 24. The medial one of the passages 20 is at all times in communication with a first port 26 which may be connected to the main stream of fluid S.

Passages 23 and 24 are related respectively to second and third ports 23B and 24A. As will be explained, fluid derived from the main source is effectively directed to ports 23B and 24A in the sequence of operation. However, the reverse may prevail in that fluid may be combined for return to the source S.

The medial passage 20 at all times is in communication with one or the other of a pair of ports 20-1 and 20-2 allowing direct flow of fluid therebetween in either position. Four lands are shown, but three lands may also be used, as will be described. Regardless, the land edges are such that while the medial passage 20 constantly communicates with the first port 26, neither of the second and third ports is ever in direct communication with the first port 26.

Thus, the basic unit is preferably a cylinder presenting two opposed expandable chambers, one at each end, and a working member in the form of a piston is disposed therein. The expandable chambers are separated by the end lands on the piston. The expandable chamber unit has a first port 26 which may be connected to a

first source of fluid S, and second and third ports 24A, 23B which may be connected to second and third sources of fluid A and B; but these three ports may be used in many different modes. Each expandable chamber unit has a fourth port and a fifth port 20-1; 20-2. Porting and valving are critical. The first, second and third ports of one cylinder always communicate with sources as shown in FIGS. 1A and 1B; and the fourth and fifth ports of one unit respectively communicate with the expandable chambers of another unit as shown in FIG. 1B as will shortly be described for a device consisting of two cylinders so connected, FIG. 2, where the ports are shown by progressive numbers one through five in circles for each cylinder.

Thus, the invention assumes an even number of expandable chamber units, at least a pair, each unit having first, second and third ports (which may be connected to fluid sources); each unit has a working member (piston) for contracting the expandable chambers and translating fluid to another unit; each unit further having a fourth port to be connected to an expandable chamber of another unit and a fifth port to be connected to an expandable chamber of another unit. There are internal passage means in the units and valve means on the working members for alternately in each unit of a basic pair

- a. establishing connection of the fourth port with the first port and the fifth port with the second port when the working member is one side of center, the 90° or 270° position of the piston; and
- b. establishing connection of the fourth port with the third port and the fifth port with the first port when the working member is at the other side of the center position.

Said connections are further characterized in that as a pair of working members alternately assume different positions two expandable chambers are always valved to a first port and an alternate one of the second and third ports.

Thus referring to FIG. 2, Cylinder 1 and Cylinder 2 are associated to divide flow or to combine flow. It will be noted that chambers 21 and 22 and passages 20, 23 and 24 of Cylinder 2, FIG. 2, bear the same reference characters as the corresponding parts of the cylinder shown in FIGS. 1 and 1A. Identical chambers incorporated in Cylinder 1 are identified by a 30 series of reference characters. This allows fluid flow to be easily traced.

The starting condition, FIG. 2, is characterized as a random position of the pistons, but is shown as one where each piston is at the extreme left-hand position of the related cylinder. The starting condition can be any position of the pistons within their respective cylinder bores, inasmuch as the first fluid pulse, being a very small amount standing alone, is of no moment especially since the fluid translating device shown in FIG. 2, will be operating over an indefinite period of times when in use to translate a relatively large quantity of fluid between the sources (S on one hand and A and B on the other). This is equally true of the other fluid translating units disclosed herein. (A and B may be assumed as representing hydraulic motors, each to receive an equal volume of operating liquid).

With further reference to FIG. 2, the stream of supply fluid to be divided or equalized is delivered to passages 20 and 30 of the cylinders through the respective first ports, one. The source fluid from S introduced to passage 30, Cylinder 1, thus flows from the first port to

the fourth port and through related passage 30-1 to the left-hand expansion chamber 21 of Cylinder 2, noting that valving land 16D of Cylinder 1 blocks the other line of potential transfer 30-2. Fluid under pressure delivered to chamber 20 of Cylinder 2 only has the effect of holding the piston of Cylinder 1 in the left-hand extreme position shown; valving land 16D of Cylinder 2 blocks flow to passage 20-2 and port five of Cylinder 2.

The first shift (see FIG. 2A) is therefore characterized by internal passage 30 of Cylinder 1 servicing the working member or piston of Cylinder 2 in that working fluid under pressure from the source S prevails in chamber 21 of Cylinder 2, driving the piston thereof from left to right resulting in the quantity of fluid in the expandible end chamber 22 of Cylinder 2 being translated to port five and passage 33 of Cylinder 1 and from thence out port three of Cylinder 1 to actuator (source) B. Thus, the lands on the piston of Cylinder 1 valve ports one and four to an expandible chamber of Cylinder 2, while valving the other expandible chamber of Cylinder 2 to ports five and three of Cylinder 1, resulting in delivery of fluid to actuator B.

The cylinder assembly is now in the course of being reset, FIG. 2A, and it should be noted at this point there is no real pause in operation, which is to say the working members begin constant motion in that as one is midway between extreme positions (90° or 270°) it valves the next unit the working member of which starts its shift in the typical circumstance. FIG. 2F charts the sequence of flow division.

Thus, referring to FIGS. 2A and 2B, the interior valving means or lands of the piston of Cylinder 1 are so positioned that passage 30 and expandible chamber 21 are connected until the piston of cylinder 1 reaches its mid position or 90° position. At this time the piston of Cylinder 2 has reached its rightmost position, FIG. 2B. Referring to FIGS. 2B and 2C, it can be seen that the piston of Cylinder 1 valves passage 30 from chamber 21 to chamber 22 and chamber 21 is connected to passage 34. The piston of Cylinder 1 continues to travel to the right, FIG. 2B, while the piston of Cylinder 12 has been reversed and it commences to travel to the left to the position shown in FIG. 2C. Referring to FIGS. 2C and 2D, it can be seen that the piston of Cylinder 2 switches the valving to Cylinder 1, FIG. 2C; the piston of Cylinder 1 is then reversed and it commences to travel to the left and the pistons reach the positions as shown in FIG. 2D. Referring to FIGS. 2D and 2E, it can be seen that the piston of Cylinder 1 has switched the valving to Cylinder 2. The piston of Cylinder 2 commences to travel to the right while the piston of Cylinder 1 completes its stroke to the left until the positions shown in FIG. 2E are reached. These are the same positions as shown in FIG. 2A. The device has completed one cycle, and this process continues as long as pressure is supplied to the unit and the pressure in ports A and B do not exceed the supply pressure at S.

The process described occurs in reverse when the unit is placed in the combining mode.

The unit must combine or divide accurately as examination will reveal that one end of each piston is ported to one of the A or B ports. As the piston reciprocates, it accepts or delivers first a pulse to one of the ports (A or B) and then to the other port.

To attain bidirectional flow, essential in certain aircraft controls, an even number of units must be utilized. We have determined this, and in fact the rule is tested by the fact that an odd number of units will di-

vide flow from a main into separate branches, or will combine flow from two branches for delivery to a main source, but will not do both in the sense of accommodating either forward or reverse flow.

The arrangement of FIG. 2 conforms to the general rule in that each cylinder (even number of cylinders) has five essential ports, aside from the openings associated with the expandible chambers thereof, for translating fluid between the device and the system in which it is installed. Thus, in the first position, FIG. 2, the passage means and valving means presented by the configured pistons, for each unit, connect the first (source) and fourth ports, (the latter in turn being connected at all times to the expandible chamber of another unit) and connect the second (source) port and fifth ports (the latter in turn being connected to the expandible chamber of another unit). Further in the second position for each working member (FIGS. 2A and 2B) connections are switched in each unit (and were switched at mid-position of each piston) so that only the first and fifth ports are connected whilst only the third and fourth ports are connected. Consequently, in the even numbered working arrangement of cylinders, a first source port of one unit is alternatively valved by its piston to the fourth and fifth ports of that unit, and the second and third (source) ports of that unit are alternatively valved to the fourth and fifth ports thereof. The fourth and fifth ports are connected to diverse expandible chambers. Therefore the first port of one unit is always connected to an expandible chamber of another unit, but the second and third (branch) ports thereof are only alternately connected to an expandible chamber of another unit; and since the two expandible chambers of one unit are respectively connected to the fourth and fifth ports of another unit, it follows that for two successive shifts (one piston, then the other) the fourth and fifth ports of two units (even number) are receiving two unit volumes (2×S) while translating half to A branch and half to B branch.

The device, FIG. 2, therefore works in reverse for if A and B are at a pressure higher than S it can be seen that B pressure entering port two of Cylinder 2, FIG. 2, transfers to port five thereof and from thence to expandible chamber 31 causing the piston therein to shift to the right, transferring fluid from chamber 32 to ports four and one of Cylinder 2, returning B to S. The piston of Cylinder 1 eventually occupies the position shown in FIG. 2C and in moving to that position valved its port three (A source) to chamber 21 of Cylinder 2 moving the piston of Cylinder 2 to the right delivering fluid in chamber 22 to the communicated ports five and one of Cylinder 1, returning A to S. In two shifts, sources A and B are combined to produce confluence at S. The piston of Cylinder 2 is now in the position shown in FIG. 2E, moving toward the position shown in FIG. 2B. High pressure at B of Cylinder 1 and B of Cylinder 2 is without effect, but high pressure at A of Cylinder 2, port 3, FIG. 2C is communicated to port four associated therewith and is transferred to the right hand expandible chamber of Cylinder 1 the piston of which is translated to the left delivering fluid to communicated ports five and one of Cylinder 2, and as it moves through mid-position ports two and five of Cylinder 1 are connected, transferring source B (working fluid) to the right-hand expandible chamber of Cylinder 2. Now, the left-hand expandible chamber of Cylinder 2 is contracted forcing fluid therein to port four of Cylinder 1 which was communicated to port one thereof (S) when

the piston of Cylinder 1 passed its mid-position aforesaid, and so on, the system constantly and alternatively relying on high pressure at sources A and B to drive the pistons to displace fluid in the end chambers for delivery to port one.

The internal medical passages 20 and 30 of each unit are constantly translating fluid between port one and an expansible chamber of another unit, being constantly switched from one expansible chamber to another, either to transfer fluid alternately to different expansible chambers in the dividing mode of operation or to receive fluid therefrom in the combining mode of operation. At the same time, a remaining one of the two internal passages, but only one, is repeatedly and alternately connected to an expansible chamber other than the expansible chamber to which the medial passage is connected, thereby to accept fluid in the dividing mode or transmit fluid in the combining mode.

The device, FIG. 2, consists of a free running pair in that as one working member moves in one direction to contract one of the expansible chambers of its cylinder, it valves, at the 90° midposition, the contracted end chamber of the other cylinder to the acting source of fluid pressure, whereupon the working member of the other cylinder starts to move and lags the first by 90°. When the other working member passes midposition it valves the contracted end chamber of the first cylinder to the acting source pressure; and so on, one working member constantly leading the other by 90°. In a free running pair, then, the pistons move repeatedly in opposite directions, translating fluid to (or from) ports two and three, and at midposition one piston valves the contracted chamber of the paired unit to the acting fluid pressure, and vice versa for the piston of the paired unit.

It will also be seen, FIG. 2, that series and reverse connections prevail. A series connection is exemplified by port five (right-hand) of Cylinder 1 being connected to the right-hand end chamber 22 of Cylinder 2, while left-hand port four thereof is connected to the left-hand end chamber 21 of Cylinder 2. The reverse connection is: right-hand port five of Cylinder 2 connected to the left-hand end chamber of Cylinder 1, and left-hand port four thereof connected to right-hand end chamber of Cylinder 1.

It will also be seen that operation of the two cylinder pairs, FIG. 2, is characterized, in the flow dividing mode (S to A; S to B) by alternate delivery as one pulse to A, one pulse to B and so on, but A and B do not get pulses at the same time; nor in the combining mode (A to S; B to S) does S get a pulse concurrently from A and B.

FIG. 3 shows a free running pair, like FIG. 2, configured to become a flow meter. There is one inlet (port one) and ports two and three are combined into one outlet for the device. Magnetic pick-ups are shown which generate pulses to an electronic counter. With a given stroke and diameter of the pistons, discrete quantities of fluid can be displaced and counted. The amount of fluid displaced may be counted by forming the ends of the pistons with ribs R, FIG. 3, each producing a digital responsive signal in the related magnetic scanner as a rib R traverses the scanner, signals being transmitted to an electronic summing (counting) device as shown in FIG. 3. Other types of pick-ups may be utilized. Proximity pick-ups of various constructions can be used instead of magnetic pick-ups, or velocity transducers may be used to measure piston rates and

consequent flow rates. Other types of pick-ups such as an LVDT may be used as piston position indicators, and electronically this can be converted to flow outputs. The preferred embodiment of a free running pair is shown in FIG. 3. However, the same concept of determining piston positions and/or velocities can be applied to other configuration constructions of more pistons.

FIG. 4 shows a hydraulic circuit breaker based on a free running pair of cylinders as in FIG. 2; port numbering is consistent with FIG. 2. In this device one piston is operated by the fluid coming from the source of supply (system) and the other piston is operated by the fluid returning from the sub-system being supplied. Should the supply of fluid from the sub-system source be interrupted, one of the pistons will not oscillate; the unit will stall in a fail safe condition.

Reference was made above to utilization of the principles of the present invention as applied to aircraft controls. In elaboration of this aspect of the invention it may be mentioned that larger aircraft may employ three hydraulic systems, two being assigned to the flight controls and the third being assigned to the landing gear. Nonetheless, some air frame manufacturers specify a fast retract for the landing gear, and in achieving this, so-called transfer units are employed by which at least one of the flight control systems supplements or augments the landing gear system for a fast retraction once the aircraft is airborne. Thus a flight control system is coupled to the third system servicing the landing gear in an augmentation mode. Additionally, the landing gear system backs up the flight control system, thus serving as a source of power should the pumps in the flight control system fail.

FIG. 5 is a schematic view of a transfer device employing two free running pairs, as defined above, interconnected with shafts. The free running pairs of cylinders oppose each other, that a change in pressure will initiate motion (as will be further explained the same principle may be used to intensify or de-intensify fluid pressure). One unit, FIG. 5, will serve as a motor and the other will serve as a pump, each being a bi-directional device able to divide flow or combine flow as mentioned above in connection with FIG. 2; but to adapt the device for unidirectional flow, a simple plunger check valve arrangement may be utilized instead of a free running pair.

More specifically, FIG. 5, Cylinders 1 and 2, 3 and 4, and the pistons associated therewith to afford a transfer unit are of the form and construction explained above in connection with FIG. 2. Cylinders 1 and 2 are combined as a free running pair in the manner of FIG. 2 (series and reverse connections) and this is equally true of Cylinders 3 and 4. The pistons of Cylinders 1 and 3 are joined by a shaft S1 whereby lateral movement of one piston is imparted to the other; the pistons of Cylinders 2 and 4 are joined in the same fashion by shaft S2.

The free running pair, Cylinders 1 and 2, may be viewed as operating in a motor mode, their pistons driving the pistons of Cylinder 3 and 4 (free running pair) operating in a pump mode. Thus, Cylinders 1 and 2 exposed to pump pressure P1 operate as a free running pair and augment the pumping action of Cylinders 3 and 4 as a free running pair. Pressure at P1 servicing Cylinders 1 and 2 may be assumed as of the order of 3,000 psi, the reservoir R1 associated therewith at a pressure of 100 psi. These values are equally applicable to pressure P2 and reservoir R2 prevailing for Cyl-

ders 3 and 4. Consequently, the pressure differential of the P1-R1 system may be viewed as transferred to an imposed on P2-R2. Thus, then P1 equals P2, no power transfer occurs; but if one system pressure fails the unit commences oscillation and pumps into the system with the lower pressure, assuming equal return pressure.

Furthermore, FIG. 5, if system pump P2 should fail, system pump P1 operating Cylinders 1 and 2 in a motor mode, as shown, will continue to drive the pistons of Cylinders 3 and 4 in a pumping mode.

If the pistons of Cylinders 1 and 2, FIG. 5 are of area greater than those of Cylinders 3 and 4, then Cylinders 1 and 2 act as an intensifier and P2 pressure will be even greater; conversely, if the piston area difference is reversed there is deintensification.

The device next to be described is one wherein actuators A and B receive pulses concurrently, characterizing smooth, instantaneous flow.

SIX UNITS

FIG. 6 illustrates operating condition for a fluid translating device embodying six cylinders. Cylinders 1, 2, 3 and 4 are ported identically to the cylinder diagrammed in FIGS. 1, 1A and 1B with the exception that ports four and five of Cylinders 1 and 4 are branched to service concurrently two expandable end chambers. Thus, the first or supply port (at S) of Cylinder 1 is constantly switched between the (branched) fourth and fifth ports thereof to service the end chambers and the pistons of Cylinders 2 and 3. Cylinder 2 is series ported and Cylinder 3 is reverse ported from Cylinder 1. The first port of Cylinder 2 is constantly switched between ports four and five thereof to service the piston of Cylinder 1, and is reverse hand connected. The first port of Cylinder 3 is constantly switched between ports four and five thereof to service the piston of Cylinder 4 by reverse hand porting.

Cylinders 5 and 6 are not ported to any source, but their expandable end chambers are reverse hand connected to (branched) ports four and five of Cylinder 4.

Examination of FIG. 6 will reveal that it consists of a free running pair (Cylinders 1 and 2) and slaved to this pair are four other pistons arranged such that smooth instantaneous flow is obtained in both the dividing and combining modes. When in the dividing mode, the following table will illustrate the pulses being delivered to the A and B ports as the piston of Cylinder 1 moves through a complete cycle. The action in combining is the reverse.

TABLE I

Piston 1 Position 90° (as shown)			Piston 1 Position 180°		
Cylinder	Ports A	B	Cylinder	Ports A	B
1	x		1	x	
2		x	2		x
3	x		3	x	
4	x		4		x
5	x		5		x
6	x		6	x	

Piston 1 Position 270°			Piston 1 Position 0°		
Cylinder	Ports A	B	Cylinder	Ports A	B
1	x		1	x	
2	x		2		x
3	x		3		x
4	x		4	x	
5	x		5	x	
6	x		6	x	

Further examination of FIG. 6 will reveal that other combinations of a flow divider/combiner are apparent if four pistons are slaved to a free running pair. As an example, instead of connecting Cylinder 3 to Cylinder 1, it could be connected to Cylinder 2. The hand of porting for the slaved piston changes, but similar results can be obtained.

Obviously additional units in combination, an even number greater than six cylinders, may be employed in achieving smooth instantaneous flow characterized by equal flow (equal volumes) to actuators A and B concurrently.

FOUR CYLINDER SYSTEM WITH BRANCHED CONDUITS

The device illustrated in FIG. 7 is characterized by four cylinders. The piston of each cylinder has two intermediate lands so that there are consistently three internal passageways between the expandable chambers at the ends of the cylinders as in the foregoing embodiments of two cylinders and six cylinders. Thus, for Cylinder 1, FIG. 7, there are three intermediate passageways 150, 151 and 152, and two expandable end chambers 153 and 154. The other three cylinders are similarly constructed.

Further, in the assembly of FIG. 7, selected conduits which transfer fluid from one cylinder to another are branched at Y-2, Y-4, Y-30 and Y-32. In order that flow of fluid may be easily traced, the pistons are shown in static, limit positions (FIGS. 7-7I) and not the instantaneous dynamic positions, but it will be understood that as a piston moves through its mid-position (90°, 270°) it valves another cylinder the piston of which starts to move.

The starting condition, FIG. 7, is purposely selected to demonstrate utilization of the Y-30 branch. Thus with the pistons set as shown in FIG. 7, passages 151, 160, 172 and 181 are exposed to the pressure of the main supply at S. Passage 151 is the only one for effectively transferring fluid and such transfer is to the expandable end chamber 163 of Cylinder 2, but nonetheless it may be pointed out with particularity that the interpositioning of land L1 of the piston of Cylinder 1 blocks transfer from the supply port (first port) of Cylinder 1 to conduit 156 leading to the end chamber 174 of Cylinder 4. Referring to the supply pressure prevailing in passage 160 of Cylinder 2 transfer to conduit 157 is blocked by interposed land L2 of the related piston, and land L3 blocks transfer of the supply pressure prevailing in passage 172 of Cylinder 4; and while supply pressure at S, Cylinder 3, is transferred to end chamber 173 of Cylinder 4 there is no movement of the piston therein which is already at its right-hand extremity. Obviously these details concerning blocked transfer or ineffective transfer need not be repeated for each of the sequences set forth hereinafter.

Consequently, a shift pulse prevails in the end chamber 163 of Cylinder 2 which moves to the right contracting end chamber 164 and transferring fluid to passage 180 of Cylinder 3. The fluid thus translated moves through the passage 180 and exits therefrom through conduit Y-30. The opposite end of branched conduit Y-30 connects to a conduit 158 which communicates with the expandable end chamber 154 of Cylinder 1 and with passage 171 of Cylinder 4. The fluid translated to Cylinder 1 is ineffective on the piston of Cylinder 1, which is already in its left-hand extremity, and consequently fluid is delivered to actuator B from passage

171.

FIG. 7A shows the second position for the piston of Cylinder 2, and the chart of FIG. 7J shows what happened.

With the pistons located as shown in FIG. 7A the only effective shift pulse is from passage 160 of Cylinder 2 to the expandable end chamber 153 of Cylinder 1. The piston of Cylinder 1 is shifted to the right, FIG. 7B, and fluid moves from end chamber 154 to passage 171, actuator B. Fluid would also tend to travel through branch Y-30 to passage 180 of Cylinder 3, and from passage 180 to end chamber 164 of Cylinder 2 tending to shift the piston of Cylinder 2 leftward, but such shift of the piston of Cylinder 2 cannot take place because its opposite end chamber 163 is communicated by conduit 159 to passage 151 in Cylinder 1 which communicates with the supply S. In other words, fluid under S pressure delivered to one end of a piston tending to shift it is ineffective to produce a shift if the expansion chamber at the opposite end of that piston is in communication with the main stream S.

Referring to FIG. 7B fluid travels from chamber 151 to passage 170 and then to end chamber 184 utilizing branch Y-4, shifting the piston of Cylinder 3, and fluid transfers from the opposed end chamber 183 to passage 161 with delivery to actuator A.

FIGS. 7C through 7H, taken with the data in FIG. 7J show that the cylinder assembly of FIG. 7 operates sequentially to deliver fluid to actuator A followed by delivery to actuator B.

It will be seen by inspection that the arrangement of FIG. 7 conforms to the general rule, Cylinders 1 and 3. Thus, for Cylinder 1 there are ports communicating with the three sources and ports four and five are respectively represented by the openings in the cylinder connected to conduits 159 and 156 respectively connected to the expandable chamber of another unit, namely, expandable chambers 163 and 174. This is shown with particularity in FIG. 71. In the first position of the piston of Cylinder 1 ports one and four, thus identified, are connected and are valved to an expandable chamber (163) of another unit while ports two (at B) and five are connected and are valved to an expandable chamber (174) of another unit. In the second position of the piston of Cylinder 1, FIG. 7C, ports one (at S) and five are connected and valved to the expandable chamber (174) of another unit while ports four and three (at A) are connected and valved to the expandable chamber (163) of another unit.

The same porting prevails for Cylinder 3, FIG. 71, bearing in mind that the branched conduits Y-30 and Y-32 are respectively identified with the second source port (B) of Cylinder 4 and the third source port (A) of Cylinder 2. In fact, this accounts for the first pulse to B, first row, FIG. 7 J and the third A pulse, fifth row, FIG. 7J.

Reverse operation of the four cylinder arrangement will be traced sufficiently to demonstrate the repetition involved, commencing with the disposition of pistons shown in FIGS. 7H. High pressure prevailing at the A port of Cylinder 1 has no effect; high pressure at the B port of Cylinder 1 is transmitted to the right-hand end chamber of Cylinder 4 (and passage 170 as well) causing the piston thereof to move to the left displacing fluid from chamber 173 to the medial passage of Cylinder 3 connected to the S port, returning fluid to S. At the same time B pressure at Cylinder 1 is transmitted through passage 170 to Cylinder 3 displacing its piston

to the left with return to S port of Cylinder 1. The piston of Cylinder 2 cannot move because the expanded end chamber thereof communicates with the expanded end chamber of Cylinder 1 and with B port of Cylinder 4 as well.

High pressure at the A port of Cylinder 2, FIG. 7H, is communicated to the left-hand expandable end chamber 153 of Cylinder 1, but without effect inasmuch as the opposed end chamber thereof communicates with passage 171 of Cylinder 4, B pressure which is equal to A pressure in Cylinder 2. Branch Y-32 also communicates with passage 161 of Cylinder 2, but there is no effect. B pressure in passage 171 of Cylinder 4 is transmitted through branch conduit Y-30 to passage 180 of Cylinder 3, but without effect.

Consequently the pistons of Cylinders 3 and 4 are the only ones repositioned, moving to the second position shown in FIG. 7F.

Referring to FIG. 7F, B pressure at Cylinder 1 has no effect. A pressure at Cylinder 1 has no effect. However, A pressure in passage 161 of Cylinder 2 is effective to drive the piston of Cylinder 1 to the right, translating fluid in the opposite end chamber thereof to passage 171 of Cylinder 4. B pressure in passage 171 of Cylinder 4 has no effect.

The following Table continues this analysis sufficiently to demonstrate the translation in the reverse sense of returning fluid from sources A and B to the source S.

Table II

FIG.	Effective Pressure	Move Piston of	Return to S at
7H	B, Cyl. 1	Cyl. 4	Cyl. 3
		Cyl. 3	Cyl. 1
7F	A, Cyl. 2	Cyl. 1	Cyl. 4
7E	A, Cyl. 2	Cyl. 4	Cyl. 1
	A, Cyl. 1	Cyl. 2	Cyl. 3
7C	A, Cyl. 2	Cyl. 3	Cyl. 1
	B, Cyl. 4	Cyl. 1	Cyl. 2
7A	B, Cyl. 1	Cyl. 4	Cyl. 3
	B, Cyl. 4	Cyl. 2	Cyl. 1
7G	B, Cyl. 4	Cyl. 3	Cyl. 1
7F	A, Cyl. 2	Cyl. 1	Cyl. 4
7E	A, Cyl. 1	Cyl. 2	Cyl. 3
	A, Cyl. 2	Cyl. 4	Cyl. 1
7C	—	—	—

Cylinders 2 and 4, FIG. 7, while having five ports between the end chambers thereof do not always have the first or S port valved to an expandable chamber. Such valving occurs at only one position shown in FIG. 7A for the valving piston of Cylinder 2 and in FIG. 7E for the valving piston of Cylinder 4. At such times the S ports are valved to respectively different expandable chambers, namely, chamber 153, FIG. 7A, and chamber 154, FIG. 7E, and from this it will be seen that the first or S port of Cylinders 2 and 4 may service the expandable end chambers of Cylinder 1.

Cylinder 2 has another port connected to the A source, and Cylinder 4 has another port connected to the B source. Collectively Cylinders 2 and 4 have a port connected to the second or third source, but not to both of the second and third sources. In a first position of the piston of Cylinder 2, FIG. 7, the A port of Cylinder 2 is communicated to a single expandable chamber, chamber 153, but as shown in FIG. 7F, the A port of Cylinder 2 may be in communication with two different expandable chambers, chambers 153 and 173. The same observations apply to port B of cylinder 4.

In the second position of Cylinder 2, FIG. 7A the A or other source port, is to be connected only to a single expandible chamber, chamber 183, and this is equally true of the second position of the piston of Cylinder 4, FIG. 7E. In any event, source ports A and B of Cylinders 2 and 4, in both positions of the valving pistons thereof, are connected to an expandible chamber of another unit, and in fact to the expandible chambers of different units in the two different positions of the working members.

It may also be a case that the second and third ports of Cylinders 1 and 3 are connected simultaneously to multiple expandible chambers presented by other units. Thus referring to FIG. 7A port B of Cylinder 1 connected to the second source is communicated by conduit 156 to expandible chamber 174 and is communicated by conduit Y-4 to expandible chamber 184 of Cylinder 3. Referring to FIG. 7D, the third source port A of Cylinder 1 is communicated by conduit 159 to expandible chamber 163 and is communicated by conduit Y-2 to expandible chamber 183. Thus it will be seen that the second source port B of Cylinder 1 may service two of the expandible end chambers one each presented by Cylinders 3 and 4, in one position of the working members, while the third source port A of Cylinder 1 may be connected to the remaining two expandible end chambers of Cylinders 2 and 3; but nonetheless, and at all times, the passage and valving means cooperate during sequencing to divide flow in a forward sense or to combine flow in a reverse sense. In this connection, it is manifestly evident that if there is an obstruction in the A source hydraulic system or B source hydraulic system all translating devices herein disclosed will stall immediately, maintaining the status quo. Thus operation assumes, in the forward mode of operation, that displacement of a piston to contract an expandible chamber will result in displacement of fluid to one of the second or third source port (A or B), but if there is an obstruction preventing delivery to actuator A or actuator B then the piston tending to displace fluid cannot move, and since it cannot move it cannot switch ports for any further translation of fluid. Clearly the reverse situation prevails, the combining mode of operation, where if there should be an obstruction of the S source then it follows that piston movement cannot displace return fluid to S in which event the related piston stalls, stalling all other pistons.

FOUR CYLINDER ARRANGEMENTS: FIG. 8, FIG. 9, FIG. 10 FIG. 8

The device shown in FIG. 8, four cylinders, is one wherein Cylinders 2 and 4 are provided with what may be termed Z porting. The static condition shown in FIG. 8 is purposely selected to show roles of the Z ports associated with Cylinders 2 and 4. S at Cylinder 1 moves piston 2 left, pulse at B1. S at Cylinder 3 moves piston 4 to the right, pulse at A3. S at Cylinder 2 moves through port five thereof to Z port of Cylinder 4 and from thence to the expandible chambers (left end) of Cylinders 1 and 3. The pistons of the latter will shift to the right, and each will translate fluid from the right end expandible chamber to Cylinder 2, Z port (two volumes) and from Z port of Cylinder 2 to Cylinder 4, two pulses at A4.

The net flow to actuators A and B is: three A, one B.

Thus, the pistons of Cylinder 2 and 4 move concurrently, in opposite directions (2L; 4R) respectively, accounting for a B pulse and an A pulse; Cylinders 1 and

3 move concurrently to the right (1R; 3R) and each delivers an A pulse released at Cylinder 4.

Consider what happens next: As the piston of Cylinder 1 is attaining its right limit position, that of Cylinder 5 2 is attaining its left position; ports one and five of Cylinder 1 are connected, valving S to Cylinder 2, and its piston moves to the right, pulse to A1 (A port of Cylinder 1). As Cylinder 3 moves to the right, it valves Cylinder 4, reversing piston 4 (to the left) which delivers a 10 pulse at B3. The pistons of Cylinders 1, 2 and 3 may be viewed as concurrently attaining the right hand limit position, while the piston of Cylinder 2 is moving from right to left with its ports five and Z connected. Consequently, S at Cylinder 2 is valved concurrently to the 15 right hand expansion chambers of Cylinders 1 and 3, the pistons of the latter move to the left and deliver pulses to communicated ports five of Z of Cylinder 4, meaning translation from Z port of Cylinder 4 to B (2) port of Cylinder 2 (two B pulses). The sum, considering 20 what happens next, is three B pulses and one A pulse.

This sequence, FIG. 8, is repeated endlessly: three A plus one B; three B plus one A; three A plus one B; etc.; as the pistons of Cylinders 1 and 3 move together in the same direction, while those of Cylinders 2 and 4 move 25 in opposite directions. Division of flow is equal, and the device combines equally in terms of reverse flow, returning A and B to S.

It will be observed that port four of Cylinder 2 is in effect branched to service ("drive") an expandible 30 chamber at one end of both Cylinders 1 and 3 in one piston position and in the other piston position port four of Cylinder 2 cooperates with the Z port of Cylinder 2 to translate fluid to port 3 (A) of Cylinder 4. Port five of Cylinder 2 is also in effect branched (through 35 Cylinder 4) to service the other expandible chambers of Cylinder 1 and 3. Likewise, Z port of Cylinder 4 alternately delivers pulses to B port of Cylinder 2.

FIG. 9

40 Multiple porting to service several expandible chambers concurrently may be accomplished in another way, FIG. 9, while using four cylinders. Cylinders 1 and 3 of the set, FIG. 9, conform to the general rule as to porting and mid-position switching as can be seen by 45 inspection and without further explanation.

Cylinder 4 is not ported to any source and the piston 50 therein becomes a slave to the fourth and fifth ports of Cylinder 3, in turn displacing fluid to either the A outlet or B outlet of Cylinder 3. Thus, Cylinder 3 valves Cylinder 4.

Cylinder 2 has two separate, isolated ports of the fourth order and two separate isolated ports of the fifth order; the piston of Cylinder 2 consequently valves both Cylinders 1 and 3 while the piston of Cylinder 1 55 valves Cylinder 2. Cylinders 1 and 2 thus become a free running pair. Nonetheless, at all times, Cylinder 2 has a first port connected to either a fourth or fifth port and a second and third port connected to either a fourth or fifth port in the alternate positions of its pistons. In fact, 60 when the piston of Cylinder 2 is in the right-hand position, FIG. 9, two ports of the first order S are connected respectively to a fourth and fifth port, while the remaining fourth port is valved to the third port A and the remaining fifth port is valved to a second port B; in the 65 left-hand position, FIG. 9A, the piston of Cylinder 2 valves two different ports of the S or first order to a fourth and fifth port while the other fourth port is valved to the third port A and the other fifth port is

valved to the second or B port.

The pistons of Cylinders 1 and 3 have two valving lands and therefore three internal passages; the piston of Cylinder 2 has four valving lands and therefore five internal passages; and since the piston of Cylinder 4 has no source port and no ports of the fourth and fifth order it is a slave to Cylinder 3 and need not have valving lands. Similarly, the pistons of Cylinders 5 and 6, FIG. 4, need not have valving lands.

FIG. 9A is presented only to illustrate the second position of each working member.

Smooth, instantaneous flow is achieved in that A and B ports receive and deliver equal volumes concurrently as an incident to concurrent translation of two pistons.

Taking the starting position as shown in FIG. 9, all pistons to the right, the sequence of operation is:

Table 3

Translation	Sequence	Delivery at
1. (P2L; P4L)*	S1; P2; A1** and S3; P4; B3	A1 plus B3
2. (P1L; P3L)	S2; P1; B2 and S2; P3; A2	B2 plus A2
3. (P2R; P4R)	S1; P2; B1 and S3; P4; A3	B1 plus A3
4. (P1R; P3R)	S2; P1; A2 and S2; P3; B2	A2 plus B2

*Read as: piston of Cylinder 2 (P2, that is) translates to the left, L, and piston of Cylinder 4 (P4) translates to the left, L.

**Read as: supply pressure prevailing at Cylinder 1 (S1) actuates the piston of Cylinder 2 (P2) resulting in an A pulse at Cylinder 1 (A1).

FIG. 10 represents another arrangement of a four piston configuration. Examination will reveal the motion of the pistons to be such that all are not in motion whether dividing or combining at the same time. This characteristic causes the pressure pulses to be non-uniform and instantaneous flow from ports A and B is not uniform. In one cycle of the machine, the total quantity of fluid moving through the machine will be accurately divided or combined. A further refinement of this concept is shown in FIG. 11. FIG. 11 is an eight cylinder device. It consists essentially of two four cylinder devices as shown in FIG. 10 in series to each other. The instantaneous flow from ports A and B are smooth with this arrangement.

Following the "hand" definition of porting to expandable chambers set forth above, it will be observed that ports four and five of Cylinder 1 are series connected to the expandable chambers of Cylinder 4, FIG. 10, equally true of the connections of ports four and five of Cylinder 4 to the expandable chambers of Cylinder 3. The series connection also prevails for the ports of Cylinder 3 connected to the expandable chambers of Cylinder 2, but Cylinder 2 services Cylinder 1 in a reverse hand.

Referring to FIG. 11, Cylinders 1 and 2 are connected in reverse hand, and Cylinders 5 and 6 are connected in reverse hand; the remaining connections are series hand.

SIX CYLINDER UNIT: CONSTRUCTION

FIGS. 12, 13 and 14 show a unitary structure 200 incorporating within a drum-like housing 202 six cylinders functioning in the manner disclosed in connection

with FIG. 6. A fixed plug or support 203 is secured centrally within the housing 202 and a machined cylinder barrel 206 is mounted thereon. The cylinder barrel is formed with six cylinders as 207 and 208. Four of the cylinders as 207, the pistons as 209 therein, the porting of the interior passages and connections to the expandable chambers as 210 conform to what is shown schematically for Cylinders 1, 2, 3 and 4, FIG. 6. Two cylinders as 208 conform to Cylinders 5 and 6, FIG. 6, which are slaves to Cylinder 4.

The way in which the section, FIG. 14, is taken does not show all the ports involved, although ports one, two, three, four and five of Cylinder 207 are apparent, which is equally true of the end connections 212 and 214 communicating the expandable chambers as 210 of Cylinder 207 with ports four and five of another cylinder.

To avoid costs of special machining, all six pistons are alike but the slave cylinders as 208 do not have internal passages ported to any source (A, B, S); only the expandable chambers thereof are ported consistent with what is shown in FIG. 6.

FIG. 15 shows the schematic plan for operating fan thrust reversers mounted on the nacelle of a jet engine. There are a set of A hydraulic cylinders (actuators) and a separate set of B hydraulic cylinders (actuators) operating mutually exclusive sets of thrust reverser flaps (not shown). Both sets are to be operated equally in unison, either in an extension sense or retraction sense.

Two six cylinder units identical to that of FIG. 12 are interposed at 200-1 and 200-2, FIG. 15. To extend the thrust reversers, fluid under pressure (from pumping source S) is delivered through conduit 221 to the corresponding S port of unit 200-1 which divides the flow to A and B, while unit 200-2 accepts and combines flow from cylinders A and B for return to the reservoir. When the thrust reversers are to be retracted, a valve (not shown) reverses the pump and return lines so that fluid under pressure from the pump (S) is delivered to conduit 222, divided by unit 200-2 to A and B while unit 200-1 combines the return flow.

THE SPECIAL CASE OF COMBINING TWO ODD NUMBER ARRANGEMENTS

FIG. 16 is a schematic view of three units; cylinder and piston construction for each unit is identical to that set forth by way of introduction, FIG. 1.

Reverse hand connections are employed uniformly for joining ports four and five of one cylinder (e.g., Cyl. 1) to the expandable chambers of another unit (e.g., Cyl. 3). However, these connections may be uniformly series, as well, or the connections may be mixed. Regardless of uniformity or mixing of such connections, the three cylinder device, FIG. 16, will divide flow equally (from S in equal parts to A and B) if that mode of operation is chosen at the start; but if chosen the device will not reverse itself to combine flow in the same system. In the dividing mode, flow is three B, three A, and so on. Conversely, the three cylinder arrangement can be started in the combining mode (combine A and B flow to S) but will not reverse to divide, regardless of how the connections are changed.

On the other hand, it has been seen that a six cylinder device, FIG. 6, works perfectly well in either direction. Consequently, a six cylinder arrangement can be viewed as a special case of two three cylinder arrangements in combination. That this is so may be realized from the fact that many alterations can be made in FIG.

6 (just as FIG. 16 may be varied as to connections) and yet the six cylinder arrangement will divide equally and combine equally. For example, referring to FIG. 6, Cylinder 1 is series connected to Cylinder 2, and Cylinder 2 is reverse connected to Cylinder 1 (one combination). But this can be reversed (another combination). Similar reversals can be made at Cylinders 5 and 6, FIG. 6, to produce other combinations.

In any event, a six cylinder device is viewed as the special case of two three cylinder devices combined so that the combination will function as a flow divider and a flow combiner in either direction which can be the essence of utility, as in FIG. 15. Nonetheless, and referring to FIG. 17, two three cylinder devices (per FIG. 16) may be used in a mutually exclusive sense. One device 230, is interposed in the supply line to divide the supply at S into equal parts for delivery to A and B sources; the other device, 231, is interposed in the return line and combines the return flow from A and B into a return confluence, back to S.

VALVING LANDS; FREE RUNNING PAIRS

Aside from the structure shown in FIG. 9, the pistons have two intermediate lands, 16C and 16D, FIG. 1; the end lands 16A and 16B characterize the piston in the first place and cooperate to define the expansible end chambers of the cylinder. However, the edges of the lands are the effective valving means. This can be understood from FIG. 18 which is a device identical to that of FIG. 2 except the pistons are formed with three lands compared to the pistons of FIG. 2 having four lands.

In FIG. 18, the left hand internal passage in the piston of Cylinder 1 connects ports one and four thereof, in the position shown, and connects port four of Cylinder 1 to the left expansible chamber of Cylinder 2, moving the piston of the latter to the right to translate fluid from the right expansible chamber of Cylinder 2 to connected ports five and two of Cylinder 1, B pulse, when working fluid S is admitted to port one of Cylinder 1.

As the piston of Cylinder 2 moves to the right, edge 240 of valve land 241, Cylinder 2, "cracks" port S of Cylinder 2, connecting it with port four of Cylinder 2, and the effect is: deliver a shift pulse to Cylinder 1; piston 1 moves to the left; and B pulse at Cylinder 2. As piston 1 moves to the left, valve edge 242 of land 243 disrupts connection between port four and S port. When valving edge 224 of land 243 "cracks" S port, the latter at the same time is connected to port five: translate working fluid to right expansible chamber of Cylinder 2; piston 2 moves to the left; delivering pulse at A(1).

As piston 2 moves to the left, valve edge 245 of land 241 opens S port to port five; and so on.

Thus it will be seen that the two intermediate land edges as 242 and 224 (two for each piston) repetitiously and alternately connect S port to ports four and five, switching at midposition in compliance with the general rule. Two other valve edges are crucial. Thus, one of the general rules is that of the source ports (A, B, S) two are never in direct communication. This is assured, FIG. 18, by the end land edges as 250 and 251 represented by the interior faces of the related piston heads 255 and 256. Thus, instead of a piston head merely defining one wall of an expansible chamber as in FIG. 2, it may be dimensioned to valve an A or B (second or third) port, as the case may be, alternately

opening and closing such port. The port A or B is opened when it is receiving fluid translated thereto from another unit (in the flow divider mode) as the working member of the other unit contracts the expansible chamber related thereto; on the other hand, the A or B port is closed when source fluid S is being delivered to the contracted expansible chamber of another unit. The device, FIG. 18, operates in a combining mode as well.

10 The two cylinder device, FIG. 18, embraces the concept of a free running pair in that each piston valves the other unit and the one piston lags the other by 90°. Series and reverse connections are involved as in FIG. 2.

15 Referring to the structure shown in FIGS. 1 and 1B, it will be recognized that the opposed inside faces of lands 16C and 16D collectively present two valving edges as the valve means for switching port S alternately to A and B. The outside faces of these two lands present two additional valving edges which valve ports 20 A and B such that when one is opened the other is closed. So again, four valve edges are involved.

25 FIG. 19 shows a two-cylinder device, embodying the concept of a free running pair, using a four-landed piston and a three-landed piston. Inspection shows that the device will divide (or combine) in the manner of the two cylinder device shown in FIGS. 2 and 18. However, series connections prevail in that each left-hand port four is connected to the left-hand expansible chamber of another unit, while each right hand port 30 five is connected to the right-hand expansible chamber of another unit.

CONCLUSION

35 It will be seen from the foregoing that the concept of a free running pair may be restricted to a two cylinder device (FIGS. 2, 18, 19) operating as a flow divider/combiner which itself may be used as a flow meter (FIG. 3) or a circuit breaker (FIG. 4) or a transfer unit (FIG. 5). A six cylinder device may be constructed to 40 include a free running pair (FIG. 6, 14) operating as a flow divider/combiner (FIG. 15); a three cylinder unit (FIG. 16) is uni-directional and can therefore be used as a flow meter, but when three more cylinders are added (FIG. 6) the device becomes bidirectional.

45 Four cylinder devices (FIGS. 7, 8, 9, 10) and eight cylinder devices (FIG. 11) are also bidirectional, which is to say they will divide flow equally (divide S between A and B) or combine equal flow (A and B to S); and a four cylinder device may embody a free running pair 50 (FIG. 9).

55 Connections may be branched (FIGS. 7 and 8); the free running pair may be modified in many ways to serve different useful purposes; characteristic ports may be multiplied (FIG. 9); and the valve structure may be varied (compare FIGS. 2, 18, 19). Consequently, variations and modifications may be made as desired by those skilled in the art without departing from the principles of the present invention.

We claim:

60 1. A cyclically operable fluid translating device comprising an even number of expansible chamber units, at least a pair, each having a pair of opposed expansible chambers and each unit including a working member repetitiously movable between first and second positions to alternately expand and contract the expansible chambers related thereto, delivery of fluid under pressure from one of the units to a contracted expansible chamber of another unit driving the related working

member of the other unit from one position to the other, each unit having first, second and third ports, a fourth port of each unit connected to an expandible chamber of another unit and a fifth port of each unit connected to another expandible chamber of another unit, internal fluid passage means in said units, valving means on each working member combined with said passage means for alternately in each unit

a. establishing connection of the fourth port with the first port and the fifth port with the second port when the working member is in the first position, and

b. establishing connection of the fourth port with the third port and the fifth port with the first port when the working member is in the second position, and the working member of one unit valving the contracted chamber of a second unit paired therewith to a source of fluid pressure prevailing at one of the first three ports of said one unit, and vice versa, so that one working member of the pair constantly lags the other.

2. A device according to claim 1 wherein each unit comprises a cylinder and each working member is a piston.

3. A device according to claim 2 wherein the expandible chambers in each cylinder are defined by the end walls of the cylinder and lands at the ends of the piston, and wherein the valve means are presented by land edges on the pistons with reduced areas between the land edges defining said internal passages.

4. A device according to claim 3 wherein the ports communicate with the reduced areas of each piston.

5. A device according to claim 1 wherein the passage means, ports and valving means associated with each unit are so located that when one working member is midway between positions said connections are switched.

6. A device according to claim 5 wherein the paired units are series and reverse connected one to the other, series connected in that the fourth and fifth ports of a first paired unit are connected to the expandible chambers of a second paired unit such that the right port is connected to the right chamber and the left port is connected to the left chamber, and reverse connected in that the fourth and fifth ports of the second unit are connected to the expandible chambers of the first unit such that the right port is connected to the left chamber and the left port is connected to the right chamber.

7. A device according to claim 5 wherein each unit is in the form of a cylinder and each working member is a piston.

8. A device according to claim 7 wherein the expandible chambers in each cylinder are defined by the end walls of the cylinder and lands at the ends of the piston, and wherein the valve means are presented by intermediate lands on the pistons with reduced areas between the piston lands defining said internal passages.

9. A device according to claim 1 comprising four of said units, a fourth port of a first unit being connected to an expandible chamber of each of a second and third unit and a fifth port of said first unit being connected to the two remaining expandible chambers of said second and third units, fourth and fifth ports of said second unit being connected to the expandible chambers of said first unit, and fourth and fifth ports of said third unit being connected to the expandible chambers of a fourth unit.

10. A device according to claim 9 including two additional units each having a pair of expandible chambers

and a working member therein but not having any of the named ports, a fourth port of the fourth unit being connected to an expandible chamber of each of the fifth and sixth units, and a fifth port of the fourth unit being connected to the remaining expandible chambers of the fifth and sixth units, whereby the fifth and sixth units are slaved to the fourth unit.

11. A device according to claim 1 wherein the working members travel 180° in moving from one position to the other, and wherein the working member in the first of a pair of units in passing the 90° position valves the contracted chamber of the paired unit to a source of fluid pressure prevailing at one of the first three ports of the first unit, and vice versa, so that one working member of the pair constantly lags the other by approximately 90°.

12. A device according to claim 11 consisting of two units.

13. Two devices according to claim 12 with the two working members of one device respectively joined to the two working members of the other device in combination as a transfer apparatus.

14. A device according to claim 12 wherein the second and third ports of one unit are each connected to a system source with the first port thereof connected to a sub-system source; and wherein the second and third ports of the second unit are connected to the sub-system source while the first port thereof is connected to the system source thereby affording a circuit breaker between the system and sub-system.

15. A device according to claim 12 in which the first port of each unit is connected to a main source of fluid and in which the second and third ports of each unit are combined to reconstitute the main source thereby affording a device having flow meter capability.

16. A device according to claim 11 comprising four of said units, a fourth port of a first unit being connected to an expandible chamber of each of a second and third unit, a fifth port of said first unit being connected to the two remaining expandible chambers of said second and third units, fourth and fifth ports of said second unit being connected to the expandible chambers of said first unit, and fourth and fifth ports of said third unit being connected to the expandible chambers of a fourth unit.

17. A device according to claim 16 including two additional units each having a working member and a pair of expandible chambers but not having any of the named ports, a fourth port of the fourth unit being connected to an expandible chamber of each of the fifth and sixth units, and a fifth port of the fourth unit being connected to the remaining expandible chambers of the fifth and sixth units, whereby the fifth and sixth units are slaves of the fourth unit.

18. A device according to claim 1 in which each working member as it passes mid-position valves the ports and passages of its unit to the passages and ports of another unit, and in which the connections are such that an expandible chamber is always interposed between one of the first three named ports of one unit and those of another.

19. A device according to claim 18 in which each unit is a cylinder and each working member is a piston, the valving means comprising four land edges on each piston spaced inward from the ends of the piston and spaced from each other, the spaces between land edges constituting internal passages.

20. A device according to claim 18 in which the valve means, ports and internal passages are such that an expansible chamber never communicates simultaneously with two of the first three ports.

21. A device according to claim 20 consisting of an even multiple of two units, the ports, passages and valving means being connected so that fluid from a first source delivered to the first port may be distributed in equal amounts to the second and third ports when there is higher pressure at the first port, or fluid at higher pressure in the second and third ports may be combined for return to the first port.

22. A device according to claim 20 wherein the pistons traverse 180° in moving from one position to the other, and wherein the piston in the first of a pair of units in passing midposition valves the contracted chamber of the paired unit to a source of fluid pressure prevailing at one of the first three ports of the first unit, and vice versa, so that one piston of the pair constantly lags the other by approximately 90°.

23. A device according to claim 22 including an even multiple of two units.

24. A device according to claim 22 wherein the fourth and fifth ports of one unit are branched, each to service the expansible chambers of two other units in the first and second positions of the working member of said one unit.

25. A cyclically operable fluid translating device for a pressure fluid system comprising an even number of expansible chamber units, at least four in number, each unit of which translates fluid under pressure between a first source of fluid and second and third sources of fluid, each unit having a pair of opposed expansible chambers, a working member in each unit repetitiously movable through 180° between first and second positions to alternately expand and contract the expansible chambers related thereto, delivery of fluid under pressure from one of the sources to a contracted expansible chamber driving the related working member from one position to the other, each unit having first, second and third ports for translating fluid between the system and the device, each unit having a fourth port connected to an expansible chamber of another unit and a fifth port connected to another expansible chamber of another unit, internal fluid passage means in said units, valving means on each working member combined with said passage means for alternately in each unit.

a. establishing connection of the fourth port with the first port and the fifth port with the second port when the working member is in the first position and

b. establishing connection of the fourth port with the third port and the fifth port with the first port when the working member is in the second position; and, for each set of four units, the working member of one unit passing midposition valving the contracted chamber of a second unit paired therewith to a source of fluid pressure prevailing at one of the first three ports of said one unit, and vice versa, so that one working member of the pair constantly lags the other by approximately 90°.

26. A device according to claim 25 consisting of four units.

27. A device according to claim 25 consisting of eight units.

28. A cyclically operable fluid translating device comprising an even number of expansible chamber units, at least a pair, each in the form of a cylinder presenting a pair of opposed expansible chambers, each cylinder having a working member in the form of a piston repetitiously movable between first and second positions within the cylinder to alternately expand and contract the expansible chambers related thereto, delivery of fluid under pressure from one cylinder to a contracted expansible chamber of another cylinder driving the related piston of the other cylinder from one position to the other, each cylinder having first, second and third ports, each cylinder having a fourth port connected to an expansible chamber of another cylinder and each cylinder having a fifth port connected to another expansible chamber of another cylinder, internal fluid passage means in said cylinders, and valving means including at least four land edges spaced from one another on each piston and related to said passage means for alternately in each cylinder

a. establishing connection of the fourth port with the first port and the fifth port with the second port when the piston is in the first position, and

b. establishing connection of the fourth port with the third port and the fifth port with the first port when the piston is in the second position,

and the piston of one unit valving the contracted chamber of a second unit paired therewith to a source of fluid pressure prevailing at one of the first three ports of said one unit, and vice versa, so that one piston of the pair constantly lags the other.

29. A device according to claim 28, wherein the pistons traverse 180° in moving from one position to the other, and wherein the piston in the first of a pair of units in passing midposition valves the contracted chamber of the paired unit, and vice versa, so that one piston of the pair constantly lags the other by approximately 90°.
